UNITED STATES PATENT OFFICE

132,540

DESIGN FOR A GARMENT HANGER

Claude A. Bradley, Reno, Nev., assignor to Handy Hangers Corporation, Reno, Nev., a corporation of Nevada

Application March 17, 1941, Serial No. 99,644

Term of patent 14 years

To all whom it may concern:

Be it known that I, Claude A. Bradley, a citizen of the United States of America, residing at Reno, in the county of Washoe and State of Nevada, have invented a new, original, and ornamental Design for a Garment Hanger, of which the following is a specification, reference being had to the accompanying drawing, forming a part thereof.

Fig. 1 is a front elevational view of a garment hanger, showing my new design;

Fig. 2 is a rear elevational view thereof, with the skirt holding members being shown as they appear in the retracted position; and

Fig. 3 is an end elevational view, both ends being the same.

I claim:

The ornamental design for a garment hanger, substantially as shown and described.

CLAUDE A. BRADLEY.
